UNITED STATES PATENT OFFICE.

ALOYS WIRSCHING AND EMIL WIRSCHING, OF BROOKLYN, NEW YORK.

PRINTING-TELEGRAPH.

SPECIFICATION forming part of Letters Patent No. 307,696, dated November 4, 1884.

Application filed April 22, 1884. (No model.)

To all whom it may concern:

Be it known that we, ALOYS WIRSCHING and EMIL WIRSCHING, both of Brooklyn, in the county of Kings and State of New York, have 5 invented certain new and useful Improvements in Printing-Telegraph Instruments; and we do hereby declare that the following is a full and exact description thereof.

This invention relates to that class of instruments in which two type-wheels are employed, 10 impressions from either of which may be produced at the will of the operator at the transmitting-station. An instrument of this character has been patented to Aloys Wirsching, 15 October 16, 1883, No. 286,667; and we will describe our present improvements as applied to an instrument constructed according to said patent; but we desire to have it well understood that our present invention may also be 20 successfully used in connection with other instruments of the same general nature.

One part of our invention relates to the means whereby the impressions are changed from one type-wheel to the other, the object 25 being to effect this automatically and without any loss of time.

The second part of our invention relates to improved means for obtaining a clear impression from one type-wheel, while the paper 30 strip is positively kept out of contact from the characters of the other type-wheel until the change is effected, by which the second wheel becomes effective instead of the first.

The accompanying drawings form a part of 35 this specification, and represent what we consider the best means for carrying out our invention.

Figure 1 is a front elevation showing the principal portions of a printing-telegraph instrument. Fig. 2 is a front elevation on a 40 larger scale, illustrating our invention. This figure shows the parts in position to receive impressions from the rear type-wheel, J'. Fig. 3 is a plan of certain portions of Fig. 2. Figs. 45 4 and 5 are corresponding plans showing modifications of Fig. 3. Fig. 6 is a diagram showing certain apparatus employed at the transmitting-station and the electrical connections at the receiving-station.

50 Similar letters of reference indicate corresponding parts in all the figures.

In these drawings we have represented the novel parts with so much of the ordinary parts as is necessary to indicate their relation there-

to. The impression-pad K, mounted at or 55 near the end of the printing-lever I, is formed, as in the above-mentioned patent, with two series of impression-surfaces, k^2 , alternating with hollow spaces, the impression-surfaces of one series being opposite the hollow spaces of the 60 other series. The pad is capable of revolving on its axis k , being controlled by the two ratchet-wheels $L' L^2$ and their pawls $M' M^2$, O being a retaining-pawl, which may be employed, if desired, but the use of which is not 65 absolutely necessary. The pawls $M' M^2$ are pivoted at a^2 , and are normally held out of contact from the ratchets $L' L^2$ by means of springs $m' m^2$, the stop m^3 serving to limit their motion. The co-operation of the pawls $M' M^2$ 70 with the ratchets $L' L^2$ and the effects thereof are exactly the same as has been fully described in the above-mentioned patent, with the exception that when one or the other pawl becomes operative the printing-pad moves 75 one step on the upward motion of the printing-lever instead of on the downward motion, as heretofore. A detailed description of such operation is therefore considered superfluous in this place.

80 The downward-projecting ends of the pawls $M' M^2$ are finished with inclined planes $m^4 m^5$, as shown, against which bears a pin, n , projecting laterally from the core N' of the electro-magnet N , which core constitutes at the 85 same time an armature, inasmuch as it is pivoted at n' , and, assuming north or south polarity, according as the spool N is energized by a positive or negative electric current, moves into contact with either the south pole 90 or the north pole of the permanent magnet N^2 . During the vibrations of the core or armature N' its pin n acts on one or the other of the inclined planes $m^4 m^5$, throwing one or the other of the pawls $M' M^2$ into position to engage 95 with its respective ratchet $L' L^2$ as soon as the printing-lever I rises to make an impression.

The arrangement of the parts $N N' N^2$ constitutes a very quick-acting polarized electro-magnet, and it will be seen that the taking of 100 impressions from one type-wheel or the other is fully controlled by energizing said electro-magnet by means of positive and negative currents. These currents must of course be transmitted by the operator from the transmitting-instrument, and it is necessary that they be transmitted over a separate wire from 105 that over which the currents for the type-wheel

magnets are transmitted. We will shortly describe an apparatus for effecting this.

Referring to the diagram, Fig. 6, A and B are two line-wires.

5 C is a transmitter of the ordinary construction, except as to additions to be described.

The wire B is connected to the ordinary pole-changing mechanism (not shown) for the service of the escapement electro-magnets.

10 The characters of one type-wheel are represented by a circle of buttons, D, while the characters of the other type-wheel are represented by a concentric row of buttons, E. The depression of any one of these buttons arrests 15 the revolving needle F and effects the printing in the well-known manner. On depressing any one of the outer buttons, metallic contact is made between said button and a ring, D'. On depressing any one of the inner buttons, 20 contact is made between it and the ring E'.

G is an auxiliary battery, one pole of which is connected to the magnets H H' by means of branching wires 1 2. The other pole of this 25 battery is connected to the needle F by wire 3. The return-wires 4 5 from the magnets H H' are connected to the rings D' E', respectively. It will now be seen that by depressing a button of the outer circle the armature I of 30 magnet H will be attracted, while by depressing a button in the inner circle the armature I' of magnet H' will be attracted, contact being established between the needle F and the rings D' or E' by means of the shank of the button which is being depressed. The armatures I and I' have each two contacts, i i', so 35 connected to the main battery J, the line-wire A, and to earth, as shown in the diagram, that when one armature, I or I', is attracted 40 a positive current is transmitted to the magnet N of the receiving-instrument, while when the other armature is attracted a negative current will be so transmitted.

It follows from the foregoing that when any 45 button of one series is depressed, one of the pawls, M' or M², assumes an operative position, and the same is the case with the other pawl on depressing any one of the other series of buttons, so that the taking of impressions from 50 one type-wheel or the other is dependent on which series of buttons the operator at the transmitting-station manipulates.

We propose to make a separate application 55 for patent for a transmitting-instrument embodying the principles herein described, and also the mode of operating herein indicated.

The printing-magnet H* of the receiver may be included in the circuit of line-wire B, as described in the above-mentioned patent; 60 but in most cases we prefer to include it in the circuit of wire A, as shown in Fig. 6, it being well understood that the sensitive magnet N becomes effective more rapidly than the printing-magnet H*, which has to overcome 65 considerable resistance, so that the pawls will always be in position before the printing-lever begins to rise.

Figs. 2 and 3 show a spring-arm, P, formed with lateral projections p, which, when the printing-lever rises, depress the paper strips 70 into the hollows formed in the printing-pad, thus stretching it over the impression-surface, whereby a clear impression is produced from the proper type-wheel, and whereby on the opposite side, where no impression shall be made 75 at the time, the paper is positively held out of contact from the type-wheel. Fig. 4 shows a similar arrangement; but in this case the arm P has two projections, p, on each side, so placed that the impression-surfaces with the paper 80 stretched over the same can just reach up between said projections to receive the impression. Fig. 5 shows two spring-arms P, one on each side of the printing-pad, each arm having two projections arranged similar to those 85 shown in Fig. 4.

We claim as our invention—

1. In a printing-telegraph instrument, the combination, with two type-wheels controlled by suitable electro-magnets, and with a revolving printing-pad, of a polarized electro-magnet, the armature or core of which serves to control the position of the printing-pad, the type-wheel-controlling electro-magnets and the printing-pad-controlling electro-magnets 95 being connected to separate line-wires, substantially as and for the purposes herein specified.

2. In a printing-telegraph instrument, the combination, with two type-wheels and a printing-pad carried on a printing-lever, of type-wheel-controlling electro-magnets, a printing-electro-magnet, and a printing-pad-controlling electro-magnet, the latter two being connected in a single line-wire circuit separate from that for the type-wheel-controlling magnets, and adapted to be operated by positive and negative currents of electricity, substantially as and for the purposes herein specified. 110

3. The combination of the polarized electro-magnet N, having an armature or core, N', with pawls, as M' M², and with a printing-pad having two series of impression-surfaces, and carrying ratchets L' L², all constructed to operate with reference to a printing-lever and to two type-wheels, substantially as herein specified. 115

4. The combination, with a printing-pad having two series of impression-surfaces alternating with hollow spaces, of one or more spring-arms, P, having lateral projections p, arranged so as to partly depress the paper into the hollow spaces when the printing-pad rises to receive an impression from either type-wheel. 125

In witness whereof we have hereunto set our hands this 21st day of April, 1884.
